US00D872156S

(12) **United States Design Patent** (10) **Patent No.:** **US D872,156 S**
(45) **Date of Patent:** **** Jan. 7, 2020**

(54) **PROTECTIVE CASE FOR CAMERA**

(71) Applicant: **SHENZHEN SI NUO XIN DA TECHNOLOGY CO., LTD.**, Shenzhen (CN)

(72) Inventor: **Chunmei Zhao**, Shenzhen (CN)

(73) Assignee: **SHENZHEN SI NUO XIN DA TECHNOLOGY CO., LTD**, Shenzhen (CN)

(**) Term: **15 Years**

(21) Appl. No.: **29/703,342**

(22) Filed: **Aug. 27, 2019**

(51) **LOC (12) Cl.** **16-01**

(52) **U.S. Cl.**

USPC **D16/200**

Primary Examiner — Ramzi S Almatrahi

(57) **CLAIM**

The ornamental design for a protective case for camera, as shown and described.

DESCRIPTION

FIG. 1 is a top perspective view of a protective case for camera showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and, FIG. 10 is an enlarged view of portion 10 shown in FIG. 1. The broken lines in the drawings depict portions of the protective case for camera that form no part of the claimed design.

1 Claim, 10 Drawing Sheets
